(57) **CLAIM**

The ornamental design for a display box, as shown and described.

DESCRIPTION

FIG. 1 is a first front perspective view of a display box showing planar objects stored in a storing compartment, showing the new design;

FIG. 2 is a second front perspective view of the display box showing a planar object partially inserted into a displaying compartment;

FIG. 3 is a front view of the display box showing the displaying compartment;

FIG. 4 is a first side view of the display box showing both the storing compartment and displaying compartment;

FIG. 5 is a rear view of the display box;

FIG. 6 is a second side view of the display box;

FIG. 7 is a top view of the display box; and,

FIG. 8 is a bottom view of the display box.

The short broken lines in the figures illustrate planar objects, which form no part of the claimed design.
